DISPENSER OF PASTY SUBSTANCES FROM
REPLACEABLE INNER CONTAINERS HAVING
THREADED FOLLOWERS

Josef Gabler, Zurich, Switzerland

Application February 25, 1948, Serial No. 10,599

6 Claims. (Cl. 222—327)

1

This invention relates to a container for dispensing pasty substances and more particularly to such a container having an interchangeable inner container.

One object of my invention is to provide a container for a creamy or pasty substance, which is to be discharged from time to time in small amounts in relation to the total content of the container, the amount discharged being accurately controlled and measured.

Another object of my invention is to provide a dispensing container of simple construction which can be operated with only one hand.

A further object is to provide a dispensing container having a maximum useful content for the pasty substance being dispensed.

Still another object is to provide a container for pasty substances which is so constructed that a replaceable inner container can be inserted therein, without requiring alignment of the inner container while it is being inserted, and the contents of the inner container can then be discharged.

A still further object of my invention is to provide a dispensing container in which a paste is caused to be emitted from a replaceable inner container through means resiliently coupled to the outer casing of the container.

Still other objects will be apparent from the following description, when read in connection with the accompanying drawing, in which:

Figure 1 is a vertical sectional view of a container embodying my invention.

Figure 2 is a horizontal sectional view on the line 2—2 of Figure 1.

Figure 3 is an elevation of a modified form of resilient coupling member employed in this container.

Figure 4 is a plan view of the resilient coupling member illustrated in Figure 3.

Figure 5 is a plan view of a disk adapted to engage the bottom of the inner container of the cream box of this invention.

Like reference characters refer to like parts throughout the several figures of the drawing.

In Figure 1 of the drawing, the numeral 1 designates the outer casing of a container having a bottom part 2, which may be either integral with or attached to the casing 1. A cover 3, of approximately the same diameter as the outer casing 1, is adapted to fit against the upper surface of the casing. A cylindrical lining or housing 4 is designed to fit inside the casing 1 with enough clearance to permit relative rotation of the housing and the casing. At its lower end,

the housing 4 is turned inwardly to form a flange 5.

A disk 6 is secured to the upper surface of the bottom 2 of the container by welding, soldering, or other suitable means. The disk 6 is provided with a peripheral recess into which the flange 5 of the housing 4 fits. The disk 6 prevents longitudinal movement of the flange 5 and the housing 4, but permits rotation of the flange and the housing with respect to the disk 6. To the upper surface of the disk 6 is secured by welding, soldering, or other suitable means, a coil spring 7 of flat cross section. The turns of the coil spring 7 have considerably greater width in a radial direction than thickness in an axial direction and the spring may be formed from sheet metal. Accordingly, when fully compressed, the spring 7 occupies a minimum of space. Moreover, by providing a spring of flat cross section, distortion of the spring when transmitting torque is substantially eliminated. To the upper end of the spring 7 is secured by welding, soldering, or other suitable means a disk 8, having in its upper surface a nonround recess 9. The recess 9 may be rectangular, star-shaped or of any other suitable nonround shape.

A replaceable inner container is so dimensioned as to fit snugly inside the housing 4. The inner container has a cylindrical side wall 10 which is threaded internally throughout its entire length. A top 11 of substantially circular shape has a flange 12 fitting into a peripheral recess at the top of the side wall 10 of the inner container. The top is formed with a central discharge opening or aperture 13, which is formed by turning a portion of the top upwardly into a circular flange. The opening 13 registers with the corresponding opening in the cover 3 of the outer casing and a dish-shaped protuberance or deposit surface 14 is formed about this latter opening. A cap 15 is provided to fit over the protuberance 14.

The bottom of the inner container is formed by a disk or piston 16, which is in screw-threaded engagement with the cylindrical wall 10 of the inner container. To the lower surface of the disk 16 is secured by welding, soldering, or other suitable means, a smaller disk 17. The disk 17 is of a suitable nonround shape to fit within and to conform closely to the recess 9 in the disk 8.

The side wall 10 of the inner container is operatively connected to the housing 4 through a spring wire 18. The wire 18 is preferably made of steel and is substantially annular in shape. At one end, the wire 18 is bent to form a pro-

jecting pin or stud 19 which extends into a notch or recess 20 in the housing 4. The opposite end of the wire 18 is bent to form another pin or stud 21 which extends into a recess or notch 22 in the bottom of the side wall 10 of the inner container. In the case of the wire 18 illustrated in Figure 1, it will be seen that the wire is in a wavy shape. In the case of the modified form of wire 28 illustrated in Figures 3 and 4, it will be seen that the wire is substantially flat, but is bent upwardly, as at 23, in order to elevate the pin or stud 21 for engagement in the notch 22 in the side wall 10 of the inner container.

In use of the container, when one inner container has been emptied, the cover 3 of the outer casing is removed and the empty container is lifted out. A full container is then inserted in the outer casing, its disk or piston 16 contacting the disk 8, as the inner container is pushed inwardly, and compressing the coil spring 7. When the new inner container is in place, the cover 3 is fitted over the top 11 of the inner container and about the housing 4 until the cover comes into contact with the upper surface of the outer casing 1. The cover 3 is dimensioned so as to fit tightly about the housing 4 and the side wall 10 of the inner container so as to transmit by friction rotation of the cover 3 to the side wall 10. In assembling a new inner container, it is not necessary to align the parts. This is done by rotating the cover 3 and thereby the side wall 10 of the inner container relative to the outer casing 1, which is connected through the bottom 2, disk 6 and coil spring 7 to the disk 8. By such rotation, a suitable amount, the disk 17 will come into alignment with the recess 9 in the disk 8 and likewise the pin or stud 21 on the wire 18 or 28 will come into alignment with and will snap into the recess or notch 22 in the bottom edge of the side wall 10. The pin or stud 19 on the other end of the wire 18 remains in contact with the recess or notch 20 in the housing 4 while inner containers are being changed.

After the parts have been assembled, as described above, measured emission of the paste contained in the inner container will be effected by holding the outer casing 1 in the palm of one hand and rotating the cover 3 with the thumb and forefinger of the same hand. As has been explained, the cover 3 is keyed by friction to the side wall 10 in the inner container and the outer casing 1 is attached to the disk 8, which through the recess 9 and cooperating disk 17 becomes keyed to the disk or piston 16. Accordingly, when the cover 3 is rotated relative to the outer casing 1, the disk or piston 16 is rotated relative to the side wall 10 of the inner container and axial movement of the disk or piston 16 is thereby effected. This causes emission of the paste through the discharge opening 13 and, it will be appreciated, due to the relatively rigid connection of the parts, the amount of paste emitted can be accurately controlled. Should an excess of paste be emitted, it can be retracted by reversing the direction of relative rotation of the parts.

It will be appreciated that there is provided by my invention a container for dispensing pasty substances in which a replaceable inner container of maximum size may be used. This is so because of my use of a coil spring of flat cross section to transmit rotational torque. The coil spring, being preferably made of flat sheet metal, has considerably more radial width than axial thickness and accordingly occupies a minimum of axial space in the outer casing when it is fully

compressed, which is when the replaceable inner container is full.

Another advantage of using a spring of flat cross section to transmit torque is that such a spring transmits the torque with a minimum of distortion, whereas a spring of round cross section readily becomes twisted out of shape.

Another advantage of the container of my invention is that it is so designed as to be operable by only one hand. Accordingly, it is very convenient in use.

The container of my invention makes possible the ready use of replaceable inner containers. In removing empty inner containers and inserting full inner containers, it is not necessary to align the new inner container with the outer casing, since the connecting parts will automatically become keyed together by rotation of the cover 3 relative to the outer casing 1. Thus, the replacement of inner containers can be effected with great facility.

I claim:

1. A container for pasty substances comprising an outer casing, a cover for said casing, a cylindrical housing inside said casing adapted for relative rotation with the outer casing, an interchangeable inner container inside said housing having a threaded inner wall, a disk secured in nonrotatable relationship with the outer casing and in screw threaded engagement with the threaded inner wall of said inner container for extruding the contents of said inner container, and means for causing relative rotation of said outer casing and disk and said inner container, said means including a spring wire compressed between the inner container and the housing and adapted to engage those members whereby they rotate as a unit.

2. A container for pasty substances comprising an outer casing, a cover for said casing, a cylindrical housing inside said casing adapted for relative rotation with the outer casing, an interchangeable inner container inside said housing having a threaded inner wall, a disk secured in nonrotatable relationship with the outer casing and in screw threaded engagement with the threaded inner wall of said inner container for extruding the contents of said inner container, means for causing relative rotation of said outer casing and disk and said inner container, said means including a spring wire locking said inner container to said housing, and a second disc secured to the bottom of the outer casing for securing the housing to the casing in rotatable relationship with the casing.

3. A container for pasty substances comprising an outer casing, a cover for said casing, a cylindrical housing inside said casing adapted for relative rotation with the outer casing, an interchangeable inner container inside said housing having a threaded inner wall, a disk secured in nonrotatable relationship with the outer casing and in screw threaded engagement with the threaded inner wall of said inner container for extruding the contents of said inner container, and means for causing relative rotation of said outer casing and disk and said inner container, said means including a substantially annular steel wire resiliently but firmly engaging at its one end a notch in said housing and at its other end a notch in said inner container.

4. A container for pasty substances comprising an outer casing, a cover for said casing, a cylindrical housing inside said casing adapted for relative rotation with the outer casing, an inter-

changeable inner container inside said housing having a threaded inner wall, a disk secured in nonrotatable relationship with the outer casing and in screw threaded engagement with the threaded inner wall of said inner container for extruding the contents of said inner container, and means for causing relative rotation of said outer casing and disk and said inner container, said means including a substantially annular steel wire resiliently but firmly engaging at its one end a notch in said housing and at its other end a notch in said inner container, said wire automatically engaging the notch in said inner container when said inner container is rotated relative to said housing.

5. A container for pasty substances comprising an outer casing, a cover for said casing, a cylindrical housing inside said casing adapted for relative rotation with the outer casing, an interchangeable inner container inside said housing having a threaded inner wall, a disk secured in nonrotatable relationship with the outer casing and in screw threaded engagement with the threaded inner wall of said inner container for extruding the contents of said inner container, and means for causing relative rotation of said outer casing and disk and said inner container, said means including a substantially annular steel wire resiliently but firmly engaging at its one end a notch in said housing and at its other end a notch in said inner container, said wire automatically engaging the notch in said inner container when said inner container is rotated relative to said housing, said wire

thereafter holding said inner container rotatively fixed with relation to said housing.

6. A container for pasty substances comprising an outer casing, a cover for said casing, a cylindrical housing inside said casing adapted for relative rotation with the outer casing, an interchangeable inner container inside housing having a threaded inner wall, a disk secured in nonrotatable relationship with the outer casing and in screw threaded engagement with the threaded inner wall of said inner container for extruding the contents of said inner container, and means causing relative rotation of said outer casing and disk and said inner container, said means including a circular wire of wavy shape, the ends of which operatively engage notches in said housing and in said inner container.
